UNITED STATES PATENT OFFICE.

HEINRICH SCHWEITZER, OF NEW YORK, N. Y.

PRESSURE APPARATUS FOR DENTAL CASTINGS.

1,107,185.

Specification of Letters Patent.

Patented Aug. 11, 1914.

Application filed December 30, 1912. Serial No. 739,266.

To all whom it may concern:

Be it known that I, HEINRICH SCHWEITZER, a subject of the German Emperor, residing at New York, in the county and State of 5 New York, have invented new and useful Improvements in Pressure Apparatus for Dental Castings, of which the following is a specification.

Casting apparatus operated with a gaseous pressure medium such as air or compressed gas usually have a flask containing the mold and a cover sealing the flask. A central perforation in the flask cover is used for the passage of the fluid pressure 10 medium into the flask. It has been found a disadvantage to force an air current directly upon the liquid metal and therefore it was suggested to use a diaphragm provided with several holes at the end of the central perforation as shown in the Figures 1 and 2 of the accompanying drawing. Such holes did not allow a uniform concentric pressure in the flask and it happened very often that one or more of the holes were obstructed and 15 that consequently the air pressure acting from only one direction toward the liquid metal forced the metal from the crucible toward the other flask side instead of forcing it centrally downward.

30 The object of my invention is the formation of a diverging, annular air passage in the cover of the pressure flask by the fixation of a disk like body at the inferior end of the central perforation leaving a circular slot peripheral to said body.

Fig. 1 of the accompanying drawing is a vertical section of a flask cover illustrating the old construction of several holes in a diaphragm at the end of the vertical perforation of a flask cover. Fig. 2 is a bottom view of the flask cover shown in Fig. 1. Fig. 3 is the lateral view with parts in section of a casting apparatus having a flask, and cover in the central perforation of which 45 a disk like body is fixed. Fig. 4 is a sectional view of a flask cover without an air dispersing body. Fig. 5 is a lateral view of a disk like body; Fig. 6 the same turned 90 degrees around its vertical axis. Fig. 7 50 shows a modified way of fastening a disk like body at the end of the vertical perforation of the flask cover. Fig. 8 is the bottom view of a flask cover with a disk like body fixed at the end of the central perforation.

Fig. 9 shows another modified way of fixing 55 a disk like body at the end of the central perforation of a flask cover; Fig. 10 is the bottom view of the flask cover shown in Fig. 9.

A uniform distribution of the fluid pressure medium in a pressure flask for castings is obtained by the arrangement of an annular slot in the flask cover concentric to the central perforation. Such annular slot requires the presence of a body which is fastened at the end of the central perforation and most preferably has a disk like shape. Various means of fastening the disk like body at the end of the perforation are shown in the accompanying drawing. In the preferred construction shown in the Figs. 3 to 6 I connect a hollow screw spindle, S, with the center of a disk, D, by a tubular piece, T, which is reduced in diameter and laterally perforated at O²—O². The interior of the connection piece, T, communicates with the hole, O', of the screw spindle, so that the pressure medium will pass from the source of pressure first through the hole, O', of the spindle, S, then through the lateral perforations, O²—O², in order to enter the interior of the flask by the annular vent, V. The end of the central perforation may be 70 conically enlarged (Fig. 4, B') and the disk 75 conically beveled (Fig. 6, B²). The screw 80 spindle, S, can be set in its end, U', against a shoulder, U², in the flask cover, C. A 85 similar construction shown in Fig. 7 necessitates the presence of a perforated diaphragm, M, in the center of which a solid 90 connection piece, P, is fastened carrying at its lower end the disk, D.

A modified way of fixing a disk, D, at the 95 end of the central perforation, R, is illustrated in Figs. 9 and 10 where the disk, D, is set against the cover, C, opposite the opening, R, by means of screws or rivets, Y—Y, and an open vent may be maintained by the washers, W—W. Without the washers, 100 W—W, the disk D, will act like a valve.

A circular vent in diverging direction is 105 of great advantage as it distributes the pressure medium most uniformly, causing pressure action upon the liquid metal to be cast uniformly from all sides.

Having now fully described my invention I claim:

A casting apparatus adapted to be oper-

ated with gaseous pressure medium having a flask and a cover provided with a central perforation, the lower end of said perforation being of conical shape, and a plug being conical shaped in its lower end; said plug fastened on said cover in such manner that an annular slot is left between cover

and plug for the purpose of discharging the pressure medium in diverging direction substantially as described and shown.

HEINRICH SCHWEITZER.
